UNITED STATES PATENT OFFICE.

PHILIP CAMINONI, JR., OF BROOKLYN, NEW YORK.

ARTICLE OF FURNITURE.

Application filed October 14, 1922. Serial No. 594,613.

To all whom it may concern:

Be it known that I, PHILIP CAMINONI, Jr., a citizen of the United States, and a resident of the city of New York, borough of Brooklyn, in the county of Kings and State of New York, have invented a new and Improved Article of Furniture, of which the following is a full, clear, and exact description.

10 This invention relates to articles of furniture of the collapsible and preferably of the readily portable type, the invention more particularly aiming to provide a new and improved cupboard, wardrobe or chifforobe.

15 The particular object of the invention is to provide a structure of the kind above indicated, and one which may be provided with different numbers of collapsible vertical walls, such as two such walls to make a corner cabinet, or three or more such walls to make a cabinet to be placed anywhere in a room, which cabinets may be readily made in different sizes, such as of comparatively great height for adults, of smaller size for 20 nurseries, and in miniature for doll houses, and as other toys, but which will be particularly characterized by a new and improved construction whereby parts are provided which at once facilitate the collapsing 25 and expanding operations and provide shelf or similar elements on the tops of which articles to be stored may be placed and from which other articles to be stored may be suspended.

30 Still other objects are to provide an article of furniture of the kind above indicated which will be simple and practical in construction, strong, durable and efficient in use, neat and attractive in appearance, and comparatively inexpensive to manufacture.

35 The invention will be more clearly understood from the following description, when taken in connection with the accompanying drawings illustrating two of the various possible embodiments of the invention.

40 In such drawings:

Fig. 1 is a front elevation of what may be termed a corner wardrobe, in expanded condition:

45 Fig. 2 is a horizontal sectional view, taken on line 2—2 of Fig. 1;

50 Fig. 3 is a view similar to Fig. 2, but showing the parts collapsed;

Fig. 4 is a vertical sectional view, taken on line 4—4 of Fig. 3;

55 Fig. 5 is a view similar to Fig. 1, but showing an embodiment having two side frames as well as a central or a back frame;

Fig. 6 is a vertical sectional view, taken on line 6—6 of Fig. 5;

60 Fig. 7 is a horizontal sectional view, taken on line 7—7 of Fig. 5;

Fig. 8 is a fragmentary view, partially broken away and partially in section, looking at the structure of Fig. 5 in side elevation or in the direction of the arrow 8 of Fig. 5, when said structure is collapsed;

65 Fig. 9 is a view similar to Fig. 7, but showing the parts collapsed;

Figs. 10 and 11 are fragmentary views, the 70 first showing a detail of construction of the structure of Fig. 1 and the second showing a detail of construction of the structure of Fig. 5, but both such details having certain underlying principles in common.

75 Similar reference characters refer to similar parts throughout the several views of the drawings.

Referring to details of Figs. 1 to 4, two vertical frames 12 are provided, here preferably identical. Each of these frames is in the present case constructed of a quadrangular wooden frame proper 13 and a panel backing 14 which may be conveniently comprised of beaver board or an analogous sheet product. It will thus be understood that as the term "frame" is used herein the same means any wall structure or member adapted in the main to be disposed in a single vertical plane.

80 85 Frames 12 are so disposed and are swingably connected for relative movement about a vertical axis as by means of hinges 15.

Associated with the two frames 12 is a combined auxiliary hinge and multi-part 90 shelf including a plurality of substantially triangular structures 16 pivotally connected as by hinges 17 along a line disposed in a horizontal plane when the structures 16 are both arranged in the same horizontal plane, 95 that is, when the wardrobe is expanded as shown in Fig. 1. In such expanded condition of the wardrobe, structures 16 thus combine to form a single larger substantially 100 triangular structure comprising a shelf, below which may be hung a bar 18 to take 105

clothes-hangers or the like. Each of the two sides of the shelf thus established which converge toward the vertical axis including the hinges 15, is pivotally mounted on a horizontal axis to one of the frames 12, as by means of a long pintle 19 as shown best in Fig. 2.

The structure just described is preferably also provided with an elastic or other suitable cord 20 anchored at its opposite ends as indicated in Fig. 1 to be stretched taut when the structure is expanded; and preferably, also, a substantially triangular sheet of canvas or other suitable flexible material, (not shown) is provided and mounted to form a roof for the wardrobe by being attached to the cord 20 and to the frames 12 along dot-and-dash lines 21, while, if desired, draw-curtains of cretonne or the like may be suspended at their tops from cord 20, as indicated by the broken lines 22 of Fig. 1. This cretonne or like curtain material, and the roof wall fabric, will, of course, desirably be chosen according to some pleasing color scheme, and in any event the parts of frames 12 will be enamelled, tinted and embellished as desired in various ways to conform with various color schemes of the rooms in which the new wardrobe is to be used.

30 In operation, to collapse the wardrobe, it is merely necessary to lift upwardly at one or both of the structures 16 near where they are joined by hinges 17, this pressure automatically causing the axis including the hinges 17 to take up an inclination to the horizontal and increase such inclination; thereby to move both frames 12 relative to the vertical axis containing hinges 17; this action continuing until the parts are disposed as shown in Figs. 3 and 4, cord 20 and the flexible members attached thereto having been meanwhile tucked into place between the frame members 12. In order to readjust the wardrobe from its collapsed to its expanded condition it is only necessary to swing the frames 12 away from each other at their outer vertical edges, until the structures 16 are again disposed as shown in Fig. 1, at which time the weight of such structures maintains the wardrobe securely and solidly expanded. It will be understood that the word "structures" has been deliberately used in describing the parts 16 in order to bring out clearly that while the same are 50 preferably made as single wooden leaves, they may be otherwise constructed, whether of unitary form or not, so long as they provide edge portions for carrying the equivalents of pintles 19 and hinges 17 in substantially the same horizontal plane when the wardrobe is expanded.

It is not certain that it will be clearly understood from the following description just how the various pivotal axes shift relatively 65 when the wardrobe is redisposed from its

expanded to its collapsed condition and vice versa. An actual model has been constructed, and it was very beautiful to watch the differing simultaneous movements of such axes. The axis containing the hinges 17 is always equi-distant from the pintles 19. Also, the three pivotal connections for the complete shelf construction, to wit, the two pintles 19 and the set of hinges 17, are along separate but converging lines when the frames 12 are in various converging planes and until said frames are arranged as shown in Fig. 4.

Smooth movements of the parts specified as above described are desirably facilitated by providing details of construction as indicated in Figs. 4 and 10, the latter being an elevational view showing a part of the rear face of one of the bars 13^a of a frame 13 the front face of which bar is shown in Fig. 4. From such Figs. 4 and 10 it will be seen that the converging ends of pintles 19 are permitted to have a play in horizontal slots 23, such slots being conveniently closed at one end by a thin metal plate 24, preferably inset, as shown in Fig. 4, or of such thin material that the same may be arranged as shown in Fig. 10. The parts thus described, it will be understood, constitute means to permit the required shifting of the axes of pintles 19 during an expanding or collapsing operation relative to the wardrobe structure; the presence of such means being advantageous where, with the shelf structures 16 arranged as shown in Fig. 1, the axes of pintles 19 and the line joining the axes to spring 17 are not in the same horizontal plane. Such plane displacement of these axes is desirable for purposes of economy; it being noted in this connection that pintles 19 run below the under surfaces of members 16, being there passed through wire staples 24, as shown in Figs. 3 and 4, while the pintles of hinges 17 are in the plane of the under surfaces of bottom bars 25 on members 16, as best indicated in Fig. 4.

Referring to the details of construction of the embodiment of Figs. 5 to 11, it will be seen that two frames 12^a and one frame 12^b are provided, hingedly connected as indicated at 15^a; this structure presenting two side frames and a central back frame, constituting a wardrobe pursuant to the invention including a plurality of frames but not necessarily a structure to be placed in the corner of a room.

It will be understood, of course, that the frames of the present embodiment may have associated therewith panel members similar to the members 14 of Fig. 1 and also equivalents of the parts 20, 21 and 22 of Fig. 1.

Referring now to the combined auxiliary hinge and multi-part shelf of Fig. 5, each side frame 12^a and the adjacent portion of back frame 13^a are joined by substantially 130

triangular leaves 16^a shaped preferably like the leaves 16 of Fig. 1 and pivotally mounted and interconnected according to the general principle of the invention, it being noted 5 that each such pair of leaves 16^a has its members pivotally interconnected by a single hinge 17^a and has one of such members pivotally mounted on a pintle 19^a, both of the remaining members 16^a being similarly 10 mounted on a common pintle 26 horizontally spanning back frame 13^a.

These two last-mentioned leaves or members 16^a are joined by a tie member or shelf structure proper 27, here a single wooden 15 board approximately as long as the width of the back frame, and suitably anchored to the two members 16^a hinged on pintle 26, as by means of suitable nails or screws (not shown) near the opposite ends of the board.

20 From the foregoing, it will be seen that in the case of the wardrobe of Fig. 5, the entire collection of leaf parts 16^a and 27 may be properly called a single shelf structure, as have been characterized hereinabove 25 the pair of parts 16 and one of such parts of Fig. 1; but it will be understood that an equally satisfactory way verbally to distinguish the different parts would be to define the parts 16 and 16^a as far as both 30 Figs. 1 and 5 are concerned, as component structures of a single complete shelf structure, while, referring to Fig. 1 solely, each part 16 may be conveniently described as a substantially triangular structure combined 35 with a fellow to form a single larger substantially triangular structure, and, referring to Fig. 5 solely, the four parts 16^a of the part 27 all taken together may be termed a complete shelf structure which includes 40 two multi-part triangular structures the parts of which are the members 16^a, which multi-part triangular structure includes two sub-structures each consisting of one of the members 16^a.

45 For the same reasons as described in connection with the structure of Fig. 1, it may be desirable to provide a mounting for parts of certain or all of the three pintles 19^a and 50 26 to provide means to permit shifting thereof, to be embodied as required. In Fig. 11, for instance, such a shifting means is shown as possibly associated with two of the leaves of any shelf structure. Hence, board 27 is not delineated, and the showing is more 55 or less diagrammatic, the opposite ends of a complete shelf structure of any type being indicated generally at X and being provided at one terminus with an arm 28 anchored on the shelf structure as shown, and 60 turning at its free end on a stud 29 on a frame Y, and provided at another terminus with a link 30 adapted to turn about studs 31 and 32 and shown as a possible alternative type of construction. It will be understood 65 that a plurality of arms 28 solely, or a plu-

rality of links 30 solely, or the use through-out of slots like the slot 23 of Fig. 10, or various combinations of such or equivalent devices, may be used in any embodiment of the invention, where required or advanta- 70 geous.

It will thus be seen that I have provided 75 illustrative embodiments of the invention well calculated to attain the various objects and advantages above expressed and indicated; it being obvious, however, that various changes may be made in the general form and arrangement of the parts described without departing from the invention, and hence I do not limit myself to the precise 80 details set forth, but consider myself at liberty to make such changes and alterations as fairly fall within the spirit and scope of the appended claims.

I claim:

1. A collapsible article of furniture including, in combination, three vertical frames comprising a central back frame and two side frames, each connected to each side of the back frame for movements of the side frames about vertical axes relative to the back frame, and a combined auxiliary hinge means and shelf structure, said shelf structure including two substantially multi-part triangular structures each pivotally 90 connected to one side frame and the back frame and each including a pair of triangular sub-structures pivotally interconnected along a side of each sub-structure, the three 95 pivotal connections mentioned for each shelf structure being along separate but converging lines when the back frame and the associated side frame are in various converging planes.

2. The article of furniture defined in 105 claim 1, wherein there is provided a tie-member rigidly connected to a sub-structure of each shelf structure.

3. The article of furniture defined in 110 claim 1, wherein there is provided a tie-member rigidly connected to the sub-structure of each shelf structure which is pivotally connected to the back frame.

4. The article of furniture defined in 115 claim 1, wherein there is provided a shelf structure proper approximately as long as the width of the back frame overlying the said sub-structure and mounted for swinging on a horizontal axis relative to the back frame.

5. The article of furniture defined in 120 claim 1, wherein there is provided a shelf structure proper approximately as long as the width of the back frame and permanently secured near its opposite ends to the two 125 sub-structures pivotally connected to the back frame.

6. A collapsible article of furniture including, in combination, a pair of vertical frames hinged together for movement of 130

one frame relative to the other about a vertical axis, and a combined auxiliary hinge means and shelf structure, said shelf structure including two triangular structures each pivotally connected along one of the edges of the triangular to one of the side frames and both said triangular structures

pivotally interconnected along another edge of the triangle of each, the three pivotal connections mentioned being along separate but converging lines when the vertical frames are in various converging planes. 10

PHILIP CAMINONI, JR.
